LOUIS H. DOERE, OF VENTURA, CALIFORNIA.

FLOW NIPPLE.

Application filed June 2, 1924. Serial No. 717,246.

My invention relates to the art of controlling the flow from oil wells. In the oil industry it is quite common to bring in large wells which have a high gas pressure and from which the oil is expelled with considerable force. If these wells are allowed to flow freely, they sometimes do considerable damage to the casing or the various fittings about the well and they usually sand up in a very short time. This sanding up may be due to the entry of large quantities of material into the well itself, or it may possibly be due to a clogging of the formations around the well. It is, of course, highly desirable to prevent the well sanding up and for this and other purposes it is common practice to provide a flow nipple, especially on wells having high gas pressure, this flow nipple consisting of a member having a constricted orifice, the member being placed in the flow line from the well and being utilized to hold a considerable gas pressure on the well, thus reducing the rate of flow and preventing damage to the well and sand troubles.

Many types of flow nipples have been invented that consist usually of a block of steel having an orifice from one-eighth to one inch in diameter. This block of steel is usually hardened to resist wear, but nevertheless due to the high velocity of the oil and gas through the orifice, a very rapid wear takes place therein.

In the conventional form of flow nipple a heavy valve is provided between the well and the flow nipple, and as the nipple wears or when it is desired to replace it with one having a different orifice, the usual method is to close this valve and then remove the flow nipple or a bushing thereof. This necessitates shutting down the well for a short period and is therefore objectionable.

It is an object of my invention to provide a flow nipple in which a new orifice may be presented without it being necessary to shut off the flow of the well. This new orifice may be of the same size or a number of different size orifices may be provided, any one of which may put in service so that the pressure built up on the well and the rate of flow of the well can be quickly controlled without shutting the well down.

Further objects and advantages will be made evident hereinafter.

Referring to the drawing which is for illustrative purposes only,

Fig. 1 is a side elevation partly in section through one embodiment of my invention.

Fig. 2 is an end view thereof showing the control handle.

Fig. 3 is a section on a plane represented by the line 3—4 of Fig. 1, showing the valve in one of its operating positions.

Fig. 4 is a section on a plane represented by the line 3—4 of Fig. 4 showing a position the valve assumes during its change from one position to another.

In the form of the invention illustrated, 11 is a valve body which is secured to a pipe 12 leading to the well to be controlled, a 70 valve not shown being preferably inserted in the pipe 12. A convenient location for the flow nipple is directly above the casing head of the well. Threaded at 13 in the member 11 is a nipple 15 which in turn is threaded 75 at 16 in a pipe 17 used as the flow line of the well. The nipple 15 in the form shown is provided with six orifices 18 which extend longitudinally therethrough and which

may be all of the same size or which may 80 be of different sizes, as shown. Seated on the inner end 19 of the nipple 15 is a valve 20 which is held centrally and turns about a pin 21.

Formed on the valve 20 is a hub 22 having a square hole therein. The valve 85 20 is also provided with an opening 23 which is somewhat larger in diameter than the largest of the orifices 18. The valve 20 may be turned by a valve stem 30, this valve stem having a square head 31 fitting in the hub 90 22 of the valve 20. The valve stem 30 projects through a plug 35 threaded at 36 in the body 11. Packing 37 compressed by a threaded gland 38 is provided about the valve stem 30 to prevent the escape of oil 95 therearound. Secured on the outer end of the valve stem 30 by means of a bolt 41 is a handle 40. The handle 40 has an inwardly projecting member 42 in which an enlarged head 43 on a bolt 44 is free to slide. The 100 head 43 has a projecting pin 45 adapted to seat in holes 46 formed on the end of the member 11. The pin 45 is forced into the holes 46 by a compression spring 47. For the purpose of locking the pin 45 in the holes 46, a guard 50 is provided, this guard being 105 pivoted at 51 on the handle 40 and being so shaped that it covers a nut 48 on the bolt

44 when it is in the position shown in the drawings. The guard 50 has a slot formed therein through which a staple 55 can project and an ordinary padlock 56 is provided 5 to lock the guard in the position shown.

The method of operation is as follows:

The holes 46 are so placed that when the pin 45 is in any of these holes the opening 23 in the valve 20 registers with one of 10 the orifices 18 in the flow nipple 15. The oil entering the interior of the body 11 through the pipe 12 is forced to flow through the opening 23 and the orifice 18, the friction of the oil passing through this orifice being sufficient to build up a substantial 15 pressure on the interior of the body 11 and on the well. This pressure may amount to several hundred pounds per square inch. Should the orifice 18 which is in service 20 wear to a sufficient degree to allow this pressure to be reduced; or should it be desired to change this pressure by changing the flow to a different size orifice, this can be accomplished by turning the valve 20. To 25 do this, it is necessary to remove the padlock 56 and turn the guard 50 back about the pivot 51 so that the operator can pull to the right, as seen in Fig. 1, on the nut 48, thus pulling the pin 45 out of the hole 46 30 with which it formerly registered. The valve stem 30 can now be turned by means of the handle 40, thus turning the valve 20 about the pin 21. The opening 23 is then moved from its position in connection with 35 one of the orifices 18 so that it connects with a second orifice. The orifices 18 are so spaced and the opening 23 in the valve 20 is sufficiently large to prevent complete shutting off of all orifices at any time. The 40 orifice 23 starts to open an orifice 18 before it entirely leaves the orifice with which it has previously been connected. This allows the well to flow continuously, and if the 45 valve is turned in the usual manner no material change in pressure takes place upon the well. Obviously, a greater or lesser number of orifices 18 than shown may be employed, and where it is not desired to change the pressure on the well but it is merely desired to give a long life to the flow nipple 15, a number of orifices all of the same size 50 may be used. The pressure of the well acts upon the valve 20 tending to hold it on its seat. The flow nipple 15 can, of course, be readily removed and replaced when it is 55 entirely worn out by closing a valve in the pipe 12.

I claim as my invention:

1. In a flow line device for a flowing well, the combination of: a hollow body constituting a valve chamber having an inlet through which to receive fluid under pressure and provided with an outlet opening; a rigid flow nipple secured in said opening 60 in fixed relation to said body and having 65

a plurality of orifices of different relative diameters through which fluid may be discharged from said valve chamber, said body and nipple being adapted to be incorporated in and form a fixed portion of a flow line; and valve means within said chamber and freely operable in relation to said fixed body and nipple to close all but one of said orifices. 70

2. In a flow line device for a flowing well, 75 the combination of: a hollow body constituting a valve chamber having an inlet through which to receive fluid under pressure and provided with an outlet opening; a rigid flow nipple secured in said opening in fixed 80 relation to said body and having a plurality of orifices of different relative diameters through which fluids may be discharged from said valve chamber, said body and nipple being adapted to be incorporated in and form a fixed portion of a flow line; and valve means within said chamber and freely operable in relation to said fixed body and nipple to selectively close all but one of said 85 orifices. 90

3. In a flow line device for a flowing well, 95 the combination of: a hollow body constituting a valve chamber having an inlet through which to receive fluid under pressure and provided with an outlet opening; a rigid flow nipple secured in said opening in fixed 100 relation to said body and having a plurality of orifices through which fluid may be discharged from said valve chamber, said body and nipple being adapted to be incorporated in and form a fixed portion of a flow line; and valve means within said chamber and freely operable in relation to said fixed body and nipple to close all but one of said orifices, said valve means being formed to at all times maintain a continuous flow through at least one of said orifices. 105

4. In a flow line device for a flowing well, 110 the combination of: a hollow body constituting a valve chamber having an inlet through which to receive fluid under pressure and provided with an outlet opening; a rigid flow nipple secured in said opening in fixed 115 relation to said body and having a plurality of orifices of different relative diameters through which fluid may be discharged from said valve chamber, said body and nipple being adapted to be incorporated in and from a fixed portion of a flow line; and valve means within said chamber and freely operable in relation to said fixed body and nipple to close all but one of said orifices, said valve means being formed to at 120 all times maintain a continuous flow through at least one of said orifices. 125

5. In a flow line device for a flowing well, 130 the combination of: a hollow body constituting a valve chamber having an inlet through which to receive fluid under pressure and provided with an outlet opening; a rigid

- flow nipple secured in said opening in fixed relation to said body and having a plurality of orifices through which fluid may be discharged from said valve chamber, said orifices extending from the inner face of said flow nipple and said body and nipple being adapted to be incorporated in and form a fixed portion of a flow line; a freely rotatable disc valve engaging said inner face of the flow nipple and having an opening adapted to register with one of said orifices; and means for operating said disc valve.
6. In a flow line device for a flowing well, the combination of: a hollow body constituting a valve chamber having an inlet through which to receive fluid under pressure and provided with an outlet opening; a rigid flow nipple secured in said opening in fixed relation to said body and having a plurality of orifices through which fluid may be discharged from said valve chamber, said orifices extending from the inner face of said flow nipple and said body and nipple being adapted to be incorporated in and form a fixed portion of a flow line; a freely rotatable disc valve engaging said inner face of the flow nipple and having an opening adapted to register with one of said orifices; means for operating said disc valve, said valve being axially movable in relation to said operating means and adapted to be maintained in close contact with the inner face of the flow nipple by the pressure within the valve chamber.
7. In a flow line device for a flowing well, the combination of: a hollow body constituting a valve chamber having an inlet through which to receive fluid under pressure and provided with an outlet opening; a rigid flow nipple secured in said opening in fixed relation to said body and having a plurality of orifices through which fluid may be discharged from said valve chamber, said orifices extending from the inner face of said flow nipple and said body and nipple being adapted to be incorporated in and form a fixed portion of a flow line; a freely rotatable disc valve engaging said inner face of the flow nipple and having an opening adapted to register with one of said orifices; and means for operating said disc valve, said means comprising a stem associated with said valve and extending outwardly from the body and having a handle at its outer end.
8. In a flow line device for a flowing well, the combination of: a hollow body constituting a valve chamber having an inlet through which to receive fluid under pressure and provided with an outlet opening; a rigid flow nipple secured in said opening in fixed relation to said body and having a plurality of orifices through which fluid may be discharged from said valve chamber, said orifices extending from the inner face of said flow nipple and said body and nipple being adapted to be incorporated in and form a fixed portion of a flow line; a freely rotatable disc valve engaging said inner face of the flow nipple and having an opening adapted to register with one of said orifices; means for operating said disc valve, said means comprising a stem associated with said valve and extending outwardly from the body and having a handle at its outer end; and means for locking said operating means in any one of its several selective positions.
9. In a flow line device for a flowing well, the combination of: a hollow body constituting a valve chamber having an inlet through which to receive fluid under pressure and provided with an outlet opening; a rigid flow nipple secured in said opening in fixed relation to said body and having a plurality of orifices through which fluid may be discharged from said valve chamber, said orifices extending from the inner face of said flow nipple and said body and nipple being adapted to be incorporated in and form a fixed portion of a flow line; a freely rotatable disc valve engaging said inner face of the flow nipple and having an opening adapted to register with one of said orifices; and means for operating said disc valve, the opening in said valve being of sufficient area to communicate with any two of said orifices so as to at all times permit a flow of fluid through the device.
- In testimony whereof, I have hereunto set my hand at Los Angeles, California, this 24th day of May, 1924.

LOUIS H. DOERR.
